TURBINE, COMPRESSOR, OR LIKE ROTARY MACHINE HAVING A PIVOTED INDICATOR BLADE RESPONSIVE TO OPERATING CONDITIONS

William Evelyn Patrick Johnson, Hampstead, London, England, assignor to Power Jets (Research and Development) Limited, London, England, a British company

Application December 27, 1948, Serial No. 67,406

Claims priority, application Great Britain
January 7, 1948

6 Claims. (Cl. 73—133)

1

This invention relates to bladed rotary fluid-flow machines, such as turbines or compressors, and is primarily concerned with machines in which the fluid-flow is in the axial direction.

One object of the invention is to afford means adapted to respond to an operating condition of the machine, and either to give an indication of variations in such operating condition, or to influence the operation of control means in accordance with such variations.

With this object in view the invention in its broad scope provides a bladed rotary fluid-flow machine such as a compressor or turbine comprising a stationary structure, in part defining a fluid flow passage through the machine, a row of stator blades supported by the said structure and disposed across the passage, a pivot mounting for at least one of the said stator blades, the axis of pivoting extending in the general direction of the machine axis, further mounting means for securely holding the remaining blades, an extension of the said movable blade beyond the confine of the passage, and an element abutting the said extension and resiliently opposing movement of the said extension, which element is operable to initiate an external indication of the extent of the said movement, whereby a reading proportional to the fluid forces acting on the movable blade is obtainable.

The invention may be used to indicate the torque of a turbine (or compressor) and therefore the power delivered or absorbed by integration with R. P. M.

For the sake of example, two constructional embodiments of the invention will now be described in greater detail with reference to the accompanying diagrammatic drawings, in which:

Figure 1 is a fragmentary transverse section through an axial flow turbine according to a first embodiment.

Figure 2 is a section on the line II—II in Figure 1.

Figure 3 is a similar view to Figure 1, but showing the second embodiment.

Figure 4 is a section on the line IV—IV of Figure 3.

In the construction shown in Figures 1-2, the casing 1 of an axial flow turbine carries stator blades, of which only one row is shown. Of that row one blade 2 is pivotally mounted on an axis parallel to that of the turbine, while the remaining blades 3 are fixed.

That part of the turbine casing adjacent the row of stator blades shown comprises a pair of annuli 4, 5, secured in abutting relationship to

each other, and to the remainder of the casing 1, by suitable axial bolts (not shown). The annuli 4, 5, are formed with complementary recesses 6, 7, which co-operate to form an opening in which the blade 2 is pivotally suspended by a pin 8, and needle bearings 9. The blade 2 is provided with an outward lever arm extension 10 connected to a suitably-supported piezo-electric pressure element 11 forming part of an electrical circuit indicated generally by 12 and which includes an electrical indicating device 13 of any suitable known type.

The tangential component of fluid force on the blade 2 causes slight movement of the blade about its pivot, resulting in deformation of the piezo-electric element 11 by the lever arm 10, thus in known manner generating in the circuit 12 an E. M. F. which produces at the indicating device 13 a response proportional to the angular displacement of the blade due to the tangential component of fluid force. This latter, being proportional to the reaction in the blade-row, is a measure of torque.

To seal a leakage of working fluid at the blade pivot a chamber 14 is provided enclosing the lever arm 10 and associated parts.

It is desirable for the pivot of the blade to be so constructed that the internal surface of the fluid passage of the machine is as uninterrupted as is possible, and leakage of fluid at the actual pivot is reduced to a minimum. To this end the pivot may, if preferred, be formed by arcuate surfaces at the blade root and complementary surfaces in the casing, as in the construction hereinafter described with reference to Figures 3 and 4.

If desired there may be more than one pivoted blade in a row, or one or more pivoted blades in successive rows. In these latter cases the measuring blades may be commonly connected to one indicator.

In the embodiment shown in Figures 3 and 4 pivotally movable stator blade 15 is secured in the abutting annuli 19, 20 which constitute part of the stator casing and are held together and to the remaining part of the stator casing by axial bolts (not shown). Arcuate surfaces 16 on the root portion of the blade 15 cooperate with corresponding arcuate surfaces formed in the recesses 17, 18 provided in the annuli 19, 20. The blade 15 has a lever arm extension 10 which, as in the previous example, is connected to a suitably supported piezo-electric element 11 forming part of an electric circuit indicated generally by 12 and including an electric indi-

cating device 13. As in the previous example the lever arm 10 is housed in a chamber 14 so as to seal any working fluid which may have leaked between the cooperating surfaces at the blade root.

As before the tangential component of fluid force on the blade 15 causes deformation of the element 11 which produces a response at the indicating device 13, thereby measuring torque.

I claim:

1. A bladed rotary fluid flow machine such as a compressor or turbine comprising a stationary casing in part defining an axially extending fluid flow passage through the machine, a row of stator blades mounted inside said casing and disposed across said passage, a pivot mounting for at least one of the said stator blades, the axis of pivoting extending in the general direction of the machine axis, mounting means for securely holding the remaining blades of the said row, a chamber external to the casing and positioned in alignment with the said pivotable blade, a lever arm on said pivotable blade extending beyond said pivot mounting into said chamber, and an element supported within the chamber abutting the said lever arm for opposing resiliently movement of the said lever arm and operable to produce electric signals which vary in proportion to the lever arm movement, and an electric circuit connected to said element for transmission of said signals, whereby signals proportional to fluid forces acting on said pivotable blade are obtained.

2. A bladed rotary fluid flow machine as claimed in claim 1 and comprising an indicator in said circuit by means of which readings of torque acting upon said pivotable blade are directly obtained.

3. A bladed rotary fluid flow machine as claimed in claim 1 and comprising arcuate surfaces at the root of said pivotable blade and complementary surfaces to said arcuate surfaces formed in said casing so as to cooperate together to form said pivot mounting.

4. A bladed rotary fluid flow machine as claimed in claim 1 in which said stationary casing comprises two abutting annuli and complementary recesses in the abutting faces of said annuli together forming an aperture through the casing, and in which the pivot mounting for said pivotable blade comprises a needle bearing within the blade and a pin passing through said bearing and extending across said aperture.

5. A bladed rotary fluid flow machine such as

a compressor or turbine comprising a stationary casing, in part defining an axially extending fluid flow passage through the machine, a row of stator blades mounted inside said casing and disposed across said passage, a pivot mounting for at least one of said stator blades, the axis of pivoting extending in the general direction of the machine axis, mounting means for securely holding the remaining blades of the said row, a chamber

10 external to the casing and positioned in alignment with the said pivotable blade, a lever arm on said pivotable blade extending beyond said pivot mounting into said chamber, a piezoelectric crystal element supported within the chamber and abutting said lever arm so as to prevent more than limited movement of said lever arm and an electric circuit connected to said element for transmission of signals therefrom which are proportional to the deformation of the element by lever arm movement, whereby signals proportional to fluid forces acting on said pivotable blade are obtained.

6. A bladed rotary fluid flow machine such as a compressor or turbine comprising a stationary structure, in part defining a fluid flow passage through the machine, a row of stator blades supported by the said structure and disposed across the passage, a pivot mounting for at least one of the said stator blades, the axis of pivoting extending in the general direction of the machine axis, further mounting means for securely holding the remaining blades, an extension of the said movable blade beyond the confines of the passage, and an element abutting the said extension and resiliently opposing movement of the said extension, which element is operable to initiate an external indication of the extent of the said movement, whereby a reading proportional to the fluid forces acting on the movable blade is obtainable.
